UNITED STATES PATENT OFFICE.

JOHN BRYAN, OF YELLOW SPRINGS, OHIO.

FREIGHT-CAR AND THE LIKE.

977,705.

Specification of Letters Patent. Patented Dec. 6, 1910.

Application filed December 1, 1909. Serial No. 530,719.

To all whom it may concern:

Be it known that I, JOHN BRYAN, a citizen of the United States, residing at Yellow Springs, in the county of Greene and State of Ohio, have invented certain new and useful Improvements in Freight-Cars and the Like, of which the following is a specification, reference being had therein to the accompanying drawings.

This invention relates to freight cars and the like, and the object of the invention is to provide means for eliminating the long delays incident to the loading and unloading of freight cars.

To this end it is a further object of the invention to provide the car proper, *i. e.*, the trucks and the parts immediately connected thereto, with a removable load container which can be attached to and detached from said car, thereby enabling the car to remain continuously in service; and further, to provide means for removing the containers from the cars and replacing the same.

In the accompanying drawings, Figure 1 is an end elevation, partly in section, showing a car equipped with my invention and means for removing the container; Fig. 2 is a side elevation of such a car; Fig. 3 is a view of such a car showing modified mechanism for removing the container from the car; Figs. 4 and 5 are other modifications of the means for removing and replacing the container; and Fig. 6 illustrates a modified form of the container.

In these drawings I have illustrated one embodiment of my invention and have shown the same as applied to a flat car of ordinary construction comprising the usual trucks 1 and a flat body portion 2. It will be understood that the term "car" or "car proper" as herein used is intended to refer to the trucks and such parts as are permanently connected thereto, including a suitable supporting member which may be either the body of a flat car or any suitable supporting frame. In the form shown in Fig. 1 a container 3 is mounted directly upon the body portion 2 of a flat car and is of a shape and size corresponding substantially to that of the ordinary coal car. This container has portions extending beyond the opposite sides of the car body 2, and, in the present instance, the floor of the container is of greater width than the width of the car body, thus causing its edges to extend beyond the corresponding edges of the car body, as shown at 4. Any suitable means may be provided for securing the container in position upon the car. In the present instance, I have shown bolts 5 pivotally connected to the car body and adapted to extend through openings in the outwardly extending edges of the container, and thus securely clamp the latter in position. Suitable mechanism is provided for lifting the container from the car to permit the car to be withdrawn, and then supporting the container in a position to be unloaded. In the present instance I have shown this mechanism as comprising two platforms 6 permanently arranged on opposite sides of the track, upon which the car rests, and arranged close to the edges of the car so as to cause portions thereof to extend beneath the outwardly extending portions 4 of the container. These platforms are vertically movable, and, to this end, are shown in Fig. 1 as mounted upon hydraulic jacks 7. The jacks for the two platforms are connected to a common source of supply and are controlled from a common point, as shown at 8. Consequently, the platforms on the opposite sides of the car will be raised and lowered in unison. After the container has been elevated and the car withdrawn, the jacks may be adjusted to support the container in that position which will best facilitate the unloading or loading thereof. After the container is loaded or unloaded, as the case may be, and is ready for removal, the hoisting mechanisms are actuated and the container again elevated to permit the cars to be placed beneath the same and then lowered to place the container on the car. During the time that the container is being loaded or unloaded the car proper is released therefrom and may be utilized for other hauling, and, in this manner, the cars may be kept in constant use, thereby greatly increasing the amount of hauling which may be accomplished with a given number of cars.

Inasmuch as the containers themselves are comparatively inexpensive to construct a large number of the same can be kept on hand and may be stored, when not in use, in such a manner as to enable them to be quickly placed in service. The construction of the containers is such as to enable them to be stored in a much more compact manner than is possible with railway cars as now constructed, and, by the use of over-

head elevating mechanism, the containers can be stored without the use of trackage by stacking the same at the side of the track or placing them in any desired positions.

5 Obviously, the hoisting mechanism for raising and lowering the containers may be of any suitable character, and, in Fig. 3 of the drawings, I have shown the platforms 6 as mounted on jacks 9, of the rack and pinion type, which may be connected one to the other and operated in unison in any suitable manner. In Fig. 5 I have shown the movable portion 10 of the jacks as extending through suitable openings 11 in a stationary 15 platform 12 and engaging the projecting portions of the containers. As here shown there are three of these jacks, but, obviously, the number can be varied to suit existing conditions.

20 It may also be desirable to raise and lower the containers by means of an overhead mechanism, and I have illustrated in Fig. 4 how this can be accomplished by means of a traveling crane, such as is commonly used in 25 railway work, and which, as here shown, comprises a frame 13 of inverted U-shape having at its lower ends rollers 14 which travel on rails 15 arranged parallel with and on opposite sides of two or more tracks. 30 The upper or horizontal portion 16 of this frame forms a track on which is mounted hoisting mechanism 17 of any suitable character. By use of such hoisting mechanism the containers cannot only be raised and 35 lowered to remove the same from and replace them on the cars, but they may also be lifted from one track to another or one container may be lifted over another. This method of handling the cars is especially 40 valuable when it is desired to remove one of several containers, arranged above a single track, without disturbing the other containers, this being accomplished by merely lifting the container from its position and carrying the same either over the 45 other containers along the track on which it is mounted or moving the same laterally to a car standing on another track.

While I have shown several different 50 mechanisms for raising and lowering the containers it is obvious that this can be accomplished in many ways other than those here shown, but these several methods serve to illustrate the manner in which the containers are used. Further, while I have 55 here shown the containers as adapted for use on an ordinary flat car, it will be obvious that they can be mounted upon any suitable supporting frame and secured thereto 60 in any suitable manner.

As a further modification of the invention I have shown, in Fig. 6, an arrangement whereby a series of containers can be mounted upon one car, this being accomplished, in 65 the present instance, by constructing the

container after the manner of a wagon-bed, which may be loaded at a point of supply, hauled to the track and placed bodily upon the car, the wheels being, in the present instance, removed to enable the containers to be placed firmly upon the car body. When the car has reached its destination these containers are removed bodily and delivered to the point of consumption. In this manner the material is handled but twice, *i.e.*, it is loaded into the containers at the point of supply and unloaded at the point of consumption and the several intermediate 75 80 85 90 95 container after the manner of a wagon-bed, which may be loaded at a point of supply, hauled to the track and placed bodily upon the car, the wheels being, in the present instance, removed to enable the containers to be placed firmly upon the car body. When the car has reached its destination these containers are removed bodily and delivered to the point of consumption. In this manner the material is handled but twice, *i.e.*, it is loaded into the containers at the point of supply and unloaded at the point of consumption and the several intermediate 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760

porting member, and a container removably mounted on said supporting member and having portions extending outward beyond the opposite sides of said supporting member, of permanently arranged platforms spaced apart to receive said trucks between them and having portions adapted to extend beneath the outwardly extending portions of

said container, and means for raising and lowering said platforms.

In testimony whereof, I affix my signature in presence of two witnesses.

JOHN BRYAN.
